FIG. - 7

UNITED STATES PATENT OFFICE

RICHARD J. O'BRIEN, OF DEPEW, NEW YORK, ASSIGNOR TO WAUGH EQUIPMENT COMPANY, OF DEPEW, NEW YORK, A CORPORATION OF MAINE

CUSHION FOR SIDE BEARINGS

Application filed July 25, 1929. Serial No. 380,825.

This invention relates to cushioning means for side bearings for railway cars, and it is an object of this invention to provide an effective cushion which is restrained from expanding beyond certain limits in order that it may always present a good yield and cushioning effect in order to eliminate severe shock and jars which usually occur in going over a road bed or the like.

10 In cars for transporting passengers, noises, vibrations and shocks resulting from contact of the wheel treads and flanges with the running rails are transmitted up thru the wheels, axles, bearings, equalizers and other parts of 15 the truck, to the car underframe and body. This invention seeks to prevent this transmission of such shocks thru the side bars.

The invention comprises the novel structure and combination of parts hereinafter described and more particularly pointed out and defined in the appended claims.

In the accompanying drawings which illustrate a preferred form of this invention, and in which similar reference numerals refer to 25 similar features in the different views:

Figure 1 is a fragmentary side elevational view of a railway car showing the side bearings supported according to this invention.

Figure 2 is an enlarged sectional view 30 through one of the side bearings.

Figure 3 is a top plan view of a cushioning element that may be used to cushion the side bearings.

Figure 4 is an enlarged sectional view taken 35 upon the line IV—IV of Figure 2.

Figure 5 is a plan view of the modified cushioning means that may be used.

Figure 6 is a fragmentary elevational view, 40 illustrating a cushion element between the body bolster and truck bolster.

In connection with this invention, there is shown a portion of the side of a railway car and its truck. One of the side bars of the car is represented by the reference numeral 1 45 with its ends secured to the transverse members 2. According to this invention, a cushion retainer 3 is placed upon the outer ends of each transverse member 2 and is suitably apertured for receiving the bolts 4 that secure 50 the side bars 1 to the beam 2. This retainer is

provided with suitable upstanding marginal flanges for confining the cushion and limiting its expansion in order that it will always impart a good yield and retain its full resiliency.

The cushion itself may assume various forms, and in Figures 3 and 5 different forms have been illustrated. In Figure 3, the cushion consists of a center plate 5 with an oblong rubber ring or element 6 attached upon each side, whereby the securing bolts 4 may pass through the oblong rubber element.

In Figure 5, there is illustrated a slightly modified form in which a plurality of circular rubber elements 7 may be secured upon one or both sides of a plate 8 with the securing bolts 4 passing through the two outermost rings.

In Figure 6, there is shown a truck bolster 9 and a body bolster 10. A resilient cushion 11 confined in a retainer is positioned adjacent one of said bolsters; in the present instance it is shown associated with the body bolster 11. The retainer 12 carries a contact block 13 that contacts the contact block 14 on the truck bolster. The retainer 12 is provided with attaching flanges 12^a, spaced from the bolster 10 and slidably supported upon the bolts 15.

It will be appreciated that these cushioning elements will tend to eliminate shocks and jars that have heretofore arisen due to the metal to metal contact of the side bars with the cross members 2, and it will further be appreciated that the cushioning elements are 80 confined against expansion beyond a certain limit, thereby insuring a good yield and cushioning effect at all times. Further, the cushioning elements are held and protected against wear and tear, and due to the fact 85 that they are securely anchored, there can be no shifting movement thereof.

I am aware that numerous details of construction may be varied through a wide range without departing from the principles of this invention, and I therefore do not purpose limiting the patent granted, otherwise than necessitated by the prior art.

I claim as my invention:

1. In a railway car, a longitudinally ex- 100

tending side bar, cross members attached to the ends thereof, resilient means between said cross members and the ends of said side bar, and means for confining and limiting the action of said resilient means.

2. In a railway car embodying a side bar and transverse members secured to the ends of said side bar, a cushion retainer upon each cross member and a resilient rubber cushion in each retainer for limited lateral expansion.

3. In a railway car having a side bar and transverse members attached to the ends of said side bar, a cushion retainer upon each side bar and a cushion element in each retainer upon each side bar and a cushion element in each retainer having an aperture for receiving the securing means of said side bar.

4. In a railway car, having a side bar, cross members secured to said side bar, expandible rubber elements between said cross members and side bar and retaining means for housing said rubber elements and limiting the expandible movement thereof.

In testimony whereof I have hereunto subscribed my name at Chicago, Cook County, Illinois.

RICHARD J. O'BRIEN.
